(57) **CLAIM**

The ornamental design for a cross tee with a hole locking tab,
as shown and described.

DESCRIPTION

FIG. 1 is an isometric view of a cross tee with a hole locking tab showing our new design;

FIG. 2 is a top plan view thereof;

FIG. 3 is a side elevational view thereof, the opposite side
being identical;

FIG. 4 is an end view thereof, the opposite end being identi-
cal; and,

FIG. 5 is a bottom view thereof.
